UNITED STATES PATENT OFFICE.

RUDOLF GOMPF, OF BERLIN, GERMANY.

MACHINE FOR NUMBERING SHEETS.

1,038,348.

Specification of Letters Patent. Patented Sept. 10, 1912.

Application filed March 7, 1912. Serial No. 682,211.

To all whom it may concern:

Be it known that I, RUDOLF GOMPF, a subject of the German Empire, and residing at 27-27^a Elisabethstrasse, Berlin, Germany, 5 have invented certain new and useful Improvements in Machines for Numbering Sheets, of which the following is a specification, such as will enable others skilled in the art of which it appertains to make and use 10 the same.

This invention permits the use in a single working process of consecutively numbering devices with large type for the production of any printed matter necessitating consecutive 15 numbering with large type.

In the production of printed matter which has to be consecutively numbered and, as is necessary for example with gummed labels for parcel-post and the like, has to have 20 figures covering an area of an inch or more it has hitherto been impossible to employ automatically adjusted numbering devices, many forms of construction of which have already been employed for a long time for 25 smaller figures, irrespective as to whether the printed matter has to be produced in sheets on the surface printing press, or continuously on rotary presses from the roll of paper. For the purpose of numbering it 30 has also hitherto been necessary, when using one or the other or both of these kinds of printing presses, to print from clichés or stereotypes, to arrange the corresponding sheets stage-like in layers and then to cut 35 these layers into larger or smaller packets. This method of production entailed great loss of time, but was impossible to avoid owing, as already mentioned, to the impossibility of being able practically to employ 40 on the press consecutively numbering devices with large type, because the area to be covered by the printing is often, in the printing or feeding direction, not much greater than the large numbers with two or 45 more digits. Smaller devices with figure-types of a height of $\frac{1}{8}$ th to $\frac{1}{2}$ " were employed long ago, more particularly on the rotary presses, because these smaller devices could be arranged easily on a single cylinder, 50 10 being the largest number required for a continuous numbering (Fig. 1, smaller device 9-0 at a). Thus a press, consisting of a pair of printing cylinders (the cylinders holding the type with the counter cylinders) and an inking mechanism for inking 55 the type of the ten devices distributed

around the circumference of the printing cylinder, suffices for continuously numbering even small sheets with such small figures. These printed matters, as a great output 60 capacity of the rotary press assists *per se* the production on a large scale, were only produced in single width, that is to say generally only in narrow strips. Then in order later to facilitate in practice the manipulation of the finished printed production it was a very easy matter with the rotary presses again to wind up or to collect together into packets the narrow paper strips 70 after having been suitably perforated. The production of this printed matter with small figures as compared with that with large figures is consequently much simpler and from a productive standpoint much more practical, irrespective of any advantages in 75 their subsequent practical employment.

Now the object of the present invention is to be able continuously to number such printed matter during its production on the rotary press also with large figures. As has 80 already been stated the sizes concerned with such gummed labels and the like are generally very small in the printing direction, often only slightly larger than numbers of three or more digits. The arrangement of 85 the 10 devices absolutely necessary for a consecutive numbering with large figures is consequently impossible on a single cylinder because with the radial position of the type their distance from middle to middle would 90 be much greater than the size of the sheet to be numbered. Furthermore the printing cylinder would have to be of such large dimensions that the great weight concentrated on one point, of the printing cylinder provided with large and very heavy printing 95 devices would necessitate exceptionally large and heavy dimensions of the whole rotary press. Now in order to overcome the disadvantage of too large dimensions of the 100 press and its parts and more particularly to permit the printing of even the smallest dimensions with large figures by large printing devices rolling off on a continuous strip of paper or stuff, the present invention provides, and this constitutes its essential features, several small printing cylinders on which the various printing devices are so practically distributed that their mutual arrangement and the arrangement of the figures, is such that there results a continuous 105 numbering from 0 to 99 or 0 to 999 as de-

sired. The length of the course of the continuous strip of paper or material from one cylinder to the other must be so regulated that each of the 10 printing devices during the rotation when rolling off on the strip of paper or stuff encounters a separate sheet of ten consecutive sheets.

Referring to the accompanying drawing:—Figure 1 shows an arrangement according to the present invention for consecutively numbering with large figures from 0 to 999, at the same time printing the small figures. Fig. 2 shows the development of some of the type disks.

15 This arrangement is chosen so as simultaneously to show in one illustration the difference between the already known system of continuously numbering with small figure-printing devices and the new invention consisting in the continuous numbering during the printing process by means of large figure-printing devices.

16 The printing cylinders *b*, *c*, *d*, *e*, *f* for the large numbering devices as well as also 25 the printing cylinder *a* for the small numbering devices are of such circumference around their rolling periphery (indicated by dotted circles in Fig. 1) as to be equal to the length of ten sheets of the paper roll 30 or textile web. The necessary ten small numbering devices *h*⁰—*h*⁹ can easily be arranged on such a printing cylinder, because each device on the circumference of the cylinder is within the dimensions of one sheet.

35 It is evident, however, from Fig. 1 that there is far too little space on a single printing cylinder to receive the ten large numbering devices *i*¹—*i*¹⁰; consequently for receiving the ten large numbering devices 40 five printing cylinders *b*, *c*, *d*, *e*, *f*, each two of which work together with one of the impression cylinders *k*, *l* are provided, whereas 45 in the form of construction shown the one printing cylinder *f* has an impression cylinder *m* which also serves for the printing cylinder *a* provided with the small numbering device. The inking of the various numbering devices is effected by means of the inking apparatus *n*, *o*, *p*. Two large numbering devices are arranged diametrically 50 opposite each other on each of the five printing cylinders *b*, *c*, *d*, *e*, *f*. Now the position of the figures of the oppositely situated numbering devices on each of the five printing cylinders must be exactly the same as the position of the figures of the oppositely situated numbering devices of a single printing cylinder provided with ten printing devices. On such a printing cylinder, as regards 55 the units, the types 0 and 5, 1 and 6, 2 and 7, 3 and 8, 4 and 9 would be situated opposite each other. The adjustment of one pair of numbering devices with respect to the four other pairs as regards their printing consecutively is very easily effected

because the correct encountering of the numbering device on a special sheet of ten consecutive sheets of the paper roll or textile web is attained by regulating the length of the course of the roll or web between the groups of cylinders. The ten numbering devices will then coöperate to form a consecutive numbering, if the paper roll or textile web is so conducted that each sheet of the roll or web occupying a definite position in the order from 0—10 correctly encounters the correspondingly adjusted device intended for its numbering. In order thus to regulate the length of the course of the paper roll or textile web *g*, adjustable stretching rollers *q*, *r* are arranged in the path of the roll or web between the impression cylinders *k*, *l* and *l*, *m*.

70 The numbering devices must be so arranged that besides the units, each numbering device has rigidly mounted another number of figures from 0—9, and on each complete revolution that 10 is inserted which corresponds to the position which the sheet reaching the printing spot at the moment occupies in the sequence of sheets that has already passed the printing spot. After ten revolutions the printing cylinder inserts the corresponding hundred which is continuously changed on each further tenth revolution, until after printing the last number with three digits, the numbering devices either re-assume their initial positions or switch on the thousands according to the 80 number of type-wheels with which each 85 numbering device is provided.

90 It is evident of course that the consecutive numbering can be effected backward instead of forward, that is to say one can begin with the thousands or hundreds, switch on to the tens and change at the units; indeed this 95 backward numbering will be that generally employed, because as already stated above, the printed matters in question are frequently rolled up again by Leporello or like 100 folding systems, so that the end of the winding-up or of the folded packet must be regarded as the commencement of the finished printed product. This circumstance has 105 been taken into consideration in the example 110 shown in the drawing in Fig. 1. Here also the unprinted strip unrolled from the paper roll or textile web *s* after being printed and consecutively numbered is wound up again 115 at *t*. In this case the numbering is effected 120 with large numbers of three digits from 999 backward down to 0, and at the printing device *i*¹ has returned to 051 and consequently at the printing device *i*² to five 125 places less that is to say to 046, at printing device *i*³ to 049 and consequently at printing device *i*⁴ to 044, at printing device *i*⁵ to 037 and consequently at printing device *i*⁶ to 032, at printing device *i*⁷ to 035 and consequently at printing device *i*⁸ to 030, at print- 130

ing device i^o to 023 and consequently at printing device i^{10} to 018. The still unprinted sheets between the cylinders k , l and l , m get arranged in order on the further passage of the strip from one printing cylinder to the other, so that the strip on leaving the printing device i^1 shows a consecutive numbering on the sheets following one after the other.

10 What I claim as new and desire to secure by Letters Patent of the United States of America is:—

15 1. A rotary press for continuously numbering the sheets in paper rolls or textile webs by printing by means of large figure-printing, comprising means for consecutively numbering with large figures and distributed among a plurality of printing cylinders arranged one behind the other in 20 pairs, an impression cylinder coöperating with each pair of the said printing cylinders, means for adjusting the length of the course of the paper roll or textile web between the pairs of printing cylinders, an inking ap-

paratus, whereby by correspondingly adjusting and operating the type wheels of the numbering devices the latter mutually co-operate to produce a consecutive numbering on the sheets of the paper roll or textile web.

25 2. A rotary press for continuously numbering the sheets in paper rolls or textile webs by printing by means of large figure-printing, comprising five printing cylinders (b, c, d, e, f), each provided with two diametrically opposite numbering devices, impression cylinders (k and l) common to the cylinders (b, c and d, e) respectively, a separate impression cylinder for the printing cylinder (f), means for adjusting the length of the course of the paper roll or textile web 30 between the pairs of printing cylinders, and an inking apparatus.

35 In witness whereof I have hereunto set my hand in presence of two witnesses.

RUDOLF GOMPF.
